COMPOSITE BARBITURIC-ACID
DERIVATIVECharles R. Miller, Indianapolis, Ind., assignor to
Eli Lilly and Company, Indianapolis, Ind., a
corporation of IndianaNo Drawing. Application June 24, 1938,
Serial No. 215,583

4 Claims. (Cl. 167—52)

It is the object of my invention to produce a barbituric sedative and hypnotic which both acts promptly and exerts a fairly uniform effect over a considerable period.

5 Many barbituric-acid derivatives are known sedatives and hypnotics. But in general those which are available from other standpoints have a fairly low and fairly constant ratio between the duration of the hypnotic effect and the time 10 of onset—for those which start their action quickly also end it quickly, and those which continue their action for a long time are slow in starting that action. In consequence, they do not give both an early-starting and a long-continuing effect.

15 I have discovered that by putting together two or more barbituric-acid derivatives which have different times of onset and different durations of action I am able to get both early starting and long duration; and, most surprisingly, that the 20 onset of action may be made to be even quicker than that of the quick-acting barbituric-acid derivative and/or that the duration of action may be made to be even greater than that of the slow-acting barbituric-acid derivative.

25 Thus, sodium isoamyl ethyl barbiturate, orally administered, ordinarily takes from thirty to forty minutes to become effective, but its effect usually continues for perhaps six to ten hours; 30 while sodium propyl-methyl-carbiny1 ethyl barbiturate, (also called sodium ethyl (1-methylbutyl) barbiturate) similarly orally administered, ordinarily takes effect within twenty to thirty minutes but usually ceases its action within 35 about five to seven hours, and sodium propyl-methyl-carbiny1 allyl barbiturate ordinarily takes effect in ten to twenty minutes but its effect usually passes off within about three to five hours. None of them, individually, gives both prompt 40 and long-continued effect.

45 But by putting together one of these three types of barbituric-acid derivatives with either or both of the others, it becomes possible to increase the ratio between the duration of action and the time of onset.

The proportion between the amounts used of the several barbituric-acid derivatives may vary as desired, in accord with the type of total effect 50 to be produced. For example, excellent results

may be obtained by the following composite products, in terms of the usual adult oral dose.

Example 1:

Sodium isoamyl ethyl barbitu-	1½ grains	5
rate		
Sodium propyl-methyl-carbiny1		
allyl barbiturate	1½ grains	

Example 2:

Sodium isoamyl ethyl barbiturate	2 grains	10
Sodium propyl-methyl-carbiny1 al-		
lyl barbiturate	1 grain	

Example 3:

Sodium isoamyl ethyl barbiturate	1 grain	
Sodium propyl-methyl-carbiny1 al-		
lyl barbiturate	2 grains	15

Example 4:

Sodium isoamyl ethyl barbitu-	1½ grains	
rate		
Sodium propyl-methyl-carbiny1		20
ethyl barbiturate	1½ grains	

Example 5:

Sodium isoamyl ethyl barbiturate	2 grains	
Sodium propyl - methyl - carbiny1		
ethyl barbiturate	1 grain	25

Example 6:

Sodium isoamyl ethyl barbiturate	1 grain	
Sodium propyl - methyl - carbiny1		
ethyl barbiturate	2 grains	30

Example 7:

Sodium propyl-methyl-carbiny1		
ethyl barbiturate	1½ grains	
Sodium propyl-methyl-carbiny1		
allyl barbiturate	1½ grains	35

Example 8:

Sodium isoamyl ethyl barbitu-	1½ grains	
rate		
Sodium propyl-methyl-carbiny1		40
ethyl barbiturate	¾ grain	
Sodium propyl-methyl-carbiny1		
allyl barbiturate	¾ grain	

Example 9:

Sodium isoamyl ethyl barbiturate	1 grain	45
Sodium propyl-methyl-carbiny1 eth-		
yl barbiturate	1 grain	
Sodium propyl-methyl-carbiny1 allyl		
barbiturate	1 grain	50

Example 10:

15   Sodium di-ethyl barbiturate..... 2 grains
Sodium isoamyl ethyl barbiturate.. 1 grain
Sodium propyl-methyl-carbinal al-
lyl barbiturate..... 1 grain

Example 11:

10   Sodium phenyl ethyl barbitu-
rate..... 1½ grains
Sodium propyl-methyl-carbinal
ethyl barbiturate..... ¾ grain
Sodium propyl-methyl-carbinal
allyl barbiturate..... ¾ grain

15   Various other combinations can be made, as
desired, for those given are merely examples.

In these examples, the corresponding barbitu-
ric acids, or other salts than the sodium salts,
may be used instead of the sodium salts if de-
sired.

20   The composite products obtained can be ad-
ministered either orally or parenterally, in the
usual manner of barbituric derivatives; although
for parenteral administration the salts and not
the acids are desirable. Oral administration is
25   usually preferred for human use.

My composite barbituric-acid derivatives are
found especially advantageous in obstetrics, in
pre-surgical anesthesia, and as hypnotics for
general use.

I claim as my invention:

1. A composite barbituric-acid derivative suit-
able for oral and parenteral administration, com-
prising sodium isoamyl ethyl barbiturate and
sodium propyl-methyl-carbinal allyl barbiturate.

2. A composite barbituric-acid derivative suit-
able for oral and parenteral administration, com-
prising sodium isoamyl ethyl barbiturate and
sodium propyl-methyl-carbinal ethyl barbiturate.

3. A composite barbituric-acid derivative suit-
able for oral and parenteral administration, com-
prising sodium propyl-methyl-carbinal allyl bar-
biturate and sodium propyl-methyl-carbinal ethyl
barbiturate.

4. A composite barbituric-acid derivative suit-
able for oral and parenteral administration, com-
prising sodium isoamyl ethyl barbiturate and
sodium propyl-methyl-carbinal allyl barbiturate
and sodium propyl-methyl-carbinal ethyl bar-
biturate.

CHARLES R. MILLER. 25
